US00D608089S

(12) **United States Design Patent**
McCoy et al.

(10) **Patent No.:** **US D608,089 S**
(45) **Date of Patent:** **** Jan. 19, 2010**

(54) **BAG**

(75) Inventors: **Ryan McCoy**, Falcon Heights, MN (US); **Daniel Joseph Hoyord**, St. Paul, MN (US); **Angela L. Baer**, Minneapolis, MN (US)

(73) Assignee: **Target Brands, Inc.**, Minneapolis, MN (US)

(**) Term: **14 Years**

(21) Appl. No.: **29/335,351**

(22) Filed: **Apr. 14, 2009**

(51) **LOC (9) Cl.** **03-01**

(52) **U.S. Cl.** **D3/232**

(58) **Field of Classification Search** **D3/232–233, D3/240–246, 318, 324; 150/100, 103–104, 150/106–110, 113, 114, 118–119**

(57) **CLAIM**

The ornamental design for a bag, as shown and described.

DESCRIPTION

FIG. 1 is a top left front perspective view of the bag.

FIG. 2 is a back view of the bag.

FIG. 3 is a front view of the bag.

FIG. 4 is a right side view of the bag.

FIG. 5 is a left side view of the bag.

FIG. 6 is a cross-sectional back view of the bag taken along line 6—6 of FIG. 4;

FIG. 7 is a cross-sectional left side view of the bag taken along line 7—7 of FIG. 2; and,

FIG. 8 is a top of the bag.

The dotted lines in FIGS. 1–8 represent stitching and as such form part of the claimed design for the bag.
